UNITED STATES PATENT OFFICE.

WHITTEN E. KIDD, OF NEW YORK, N. Y.

MOLD FOR PRESSING BONNET-FRONTS.

Specification forming part of Letters Patent No. 11,996, dated November 28, 1854; Reissued January 13, 1857, No. 421.

To all whom it may concern:

Be it known that I, WHITTEN E. KIDD, of the city, county, and State of New York, have invented, made, and applied to use certain new and useful Improvements in Molds or Shapes for Pressing Buckram or Willow Bonnet-Fronts; and I do hereby declare that the following is a full, clear, and exact description of the construction and operation of the same, reference being had to the annexed drawing, making part of this specification, wherein—

Figure 1, is a plan of the mold as in use; Fig. 2, is a plan of the lower mold; and Fig. 3, is a vertical section through line 1, 1.

The like marks of reference denote the same parts in all the figures.

In the construction of buckram or similar frames for bonnets the front is made of a separate piece from the crown, the two being attached by moisture causing the gummy substance in said frames to adhere when pressed together with a hot iron.

In order to form the front piece into the necessary curved shape with the lower parts or points of said front turned off at a curve, a mold or shape has to be used, said mold being heated and having another mold or die to fit the same between which the dampened buckram or other material is pressed and dried, said mold acting on a flat strip of buckram to form the ends curved and then the strip is bent around into the conical form by hand and attached to the crown. Solid conical dies have also been used to form the fronts in a conical shape, but in this case the front cannot be pressed with curved ends on account of the difficulty of holding the strip in the required position, as the die covered the whole strip.

My invention as distinguished from the foregoing consists in constructing the dies in such a manner as to be adapted for pressing a peculiar compound curved shape or front and all or nearly all sizes of fronts can be pressed by one pair of dies, by so forming the upper die that it is adapted to cover all but a very small piece of the points of said front, which are held by the workman, and that, whether the fronts be large or small.

a, is a table or bench on which a circular iron plate *b*, with a cylindrical flanch is placed.

c, is a mold of sheet copper of sufficient thickness formed into the required shape of the bonnet front, whatever that shape may be. The upper part of this mold is left open so that a heater *d*, of any suitable construction can be placed therein.

e, is a mold or matrix constructed so as to fit closely into the mold *c*, and this mold is attached by bands 2, 2, to an arm or lever *f*, which is fitted and actuated in any usual manner so as to give the required pressure on the material when laid on the lower mold.

3, 3, are pins to which heaters may be hung should they be required, but I have generally found that the heater *d*, (confined by the cover 4) is sufficient to heat both molds by the conducting power of the copper or other material. By reference to the dotted lines in Fig. 2, it will be seen that when a strip of buckram or other material (cut out in the shape shown in Fig. 4) is laid on said mold, the ends or points approach each other. Now with a large sized bonnet, the strips are wider and longer, consequently the points require to be farther apart, and farther out on the mold as shown by the outer dotted lines, but with smaller sizes the strip of material has to be so placed that the ends approach each other nearer, and in consequence of the strip being narrower, require to be closer in on the mold. I therefore mark on said mold gage points 5, 5, to which the points of the different sizes are brought, which determine the position and accurately gage the same making a uniform and perfect shape. In order therefore to enable the workman to hold onto the very ends of the front, whatever its shape may be, I cut out of the upper mold a curved opening *g*, passing about half an inch inside all the gage points when the dies are together, thus pressing all sizes of bonnet fronts and leaving only a very small piece thereof outside said opening for the fingers to guide and sustain the front; with some character of fronts it may be necessary to guide the ends of the buckram by marks on the mold *c*, in the position shown at 6, 6, Figs. 1 and 2.

I do not claim a conical mold as this has before been used, but I am not aware that a mold with the curved opening *g*, covering all the front, (of whatever size) but the

very ends, by which the workman guides the strips, has ever before been used,

Therefore what I desire to secure by Letters Patent is,

- 5 I claim the method herein described of constructing the die *e*, with the curved opening *g*, in its side for the purpose of enabling the workman to guide and steady the material of which the front is composed, what-

ever the sized front may be, substantially as specified.

In witness whereof I have hereunto set my signature this twentieth day of October 1854.

WHITTEN E. KIDD.
